UNITED STATES PATENT OFFICE.

STANLEY J. TOBIASZ, OF CHICAGO, ILLINOIS.

ASH-SIFTER.

No. 861,199.

Specification of Letters Patent.

Patented July 23, 1907.

Application filed May 13, 1907. Serial No. 373,281.

To all whom it may concern:

Be it known that I, STANLEY J. TOBIASZ, a subject of the Emperor of Austria-Hungary, residing at Chicago, in the county of Cook and State of Illinois, have 5 invented certain new and useful Improvements in Ash-Sifters, of which the following is a specification.

The object of the invention is to provide an ash sifter so inclosed as to prevent the escape of dust or dirt and at the same time enable the ready insertion of raw ashes 10 and the removal of the sifted ashes and coals.

The invention consists in the features of construction and combination of parts hereinafter described and claimed.

In the drawings, Figure 1 is a front elevation of the 15 ash box showing the door removed; Fig. 2 a sectional elevation showing the side of the sifter box; and Fig. 3 a perspective view of the sifter box.

The ash box, as a whole, is in the form of a rectangular box 4, having side walls 5, a rear wall 6, a roof 7, and 20 a front cross wall 8. The cross wall is of a size to provide an upper opening, closed by means of a hinged door 9, and a lower opening into which is entered a drawer 10. Immediately above the drawer the walls of the ash box are provided with a strip of metal 11, in 25 the form of a chute adapted to divert the siftings into the drawer. Within the ash box is located a rotatable sifter box 12 comprising sides 13, each of which has a curved upper portion 14, and between the curved upper edges of the side walls of the box is stretched a 30 screen 15. The rear end of the screen is secured to a cross rail 16, and the front portion of the screen is in the form of a door 17 secured to the main portion by means of rings or hinges 18. The lower front edge of the door portion is secured to a door cross rail 19, which, when 35 the door is closed, is immediately above and in alignment with a fixed front cross rail 20, to which the door section is secured by means of a hook 21. In addition to the front and rear cross rails the sides are secured together by means of cross sills 22 extending across the 40 bottom of the box; and inside of the side walls and extending from end to end of the spotter box are downwardly sloping inner side walls 23, the lower edges of which rest upon the cross sills 22, and these inner side walls serve the double purpose of bracing the main side 45 walls and also providing a socket for the reception of a tapered pan 24, the formation of which permits it to be wedged tightly in place between the sloping inner side walls. The sifter box is mounted on trunnions 25 and 26 which extend through the side walls of the ash 50 box, and the trunnion 26 is extended and has secured thereto a handle 27 which permits the sifter box to be rotated.

In use, when it is desired to sift a quantity of ashes,

the hinged door 9 of the outer sifter box is opened, and thereafter the hinged screen door 17 is interlocked and 55 lifted back, which permits a pan of ashes to be inserted into the interior of the sifter box and wedged in place between the sloping or converging side walls 23. After the screen door has been fastened down and the main door of the ash box closed, the sifting operation is performed by turning the handle and rotating the sifter box. This operation serves to agitate the ashes, and with every revolution the fine particles and dust are dropped through the screen, the unburned coals remaining within the pan of the sifter box. After the 60 sifting operation is completed, the pan can be removed, and likewise the lower drawer 10, which contains the siftings, can be removed and emptied in preparation for further operations.

The invention is one which permits the easy insertion of ashes carried in a pan and undisturbed prior to the closing of the ash box door. This obviates the creation of dust incident to ordinary ash sifters in which the ashes are dumped out of a pan or back into the sifter prior to the closing of the same. In the present instance, no disturbance is created until the ashes are finally deposited in position to be sifted and the door shut. At the same time the same pan which serves for the transportation of the unsifted ashes will serve for the carrying of the reclaimed coals, which 75 renders the operation simple, easy and unattended by any objectionable features.

What I regard as new and desire to secure by Letters Patent is:

1. In an ash box, the combination of an inclosing box 85 provided with a door, and a rotatably mounted sifting box comprising flat side walls provided with curved upper edges, a screen connecting said curved upper edges, cross connections for the bottom and ends of the flat side walls of the box, downwardly sloping inner side walls constituting braces between the outer side walls and the bottom cross connections, and an ash pan having downwardly 90 converging side walls adapted to be wedged into place between the inner sloping side walls, and a handle for revolving the sifter box, substantially as described. 95

2. In an ash box, the combination of an inclosing box provided with a door, and a rotatably mounted sifting box comprising flat side walls provided with curved upper edges, a screen connecting said curved upper edges, a portion of said screen being hinged to provide a door, cross connections for the bottom and ends of the flat side walls of the box, downwardly sloping inner side walls constituting braces between the outer side walls and the bottom cross connections, and an ash pan having downwardly converging side walls adapted to be wedged into place between the inner sloping side walls, and a handle for revolving the sifter box, substantially as described. 100 105
